BABY CHAIR AND TABLE COMBINATION

Donald B. Cerf, 309 E. Live Oak, San Gabriel, Calif.

Filed May 10, 1965, Ser. No. 85,196

Term of patent 14 years

(Cl. D15—1)

FIG. 1 shows in front perspective a view of my design for a baby chair and table combination;

FIG. 2 shows the baby chair and table combination in front elevation; and

FIG. 3 is a side view of my baby chair and table combination.

I claim:

The ornamental design for a baby chair and table combination, substantially as shown.
